CLAIM

The ornamental design for a payment card with a machine-readable code surface, as shown and described.

DESCRIPTION

FIG. 1 is a front view of the payment card with a machine-readable code surface showing our new design; and, FIG. 2 is a rear view thereof showing our new design. The broken lines showing a portion of the payment card with the machine-readable code surface is included for the purpose of illustrating an environmental structure and form no part of the claimed design.

1 Claim, 2 Drawing Sheets

FIG. 1

FIG. 2

UNITED STATES PATENT AND TRADEMARK OFFICE
CERTIFICATE OF CORRECTION

PATENT NO. : D1,032,718 S
APPLICATION NO. : 29/868141
DATED : June 25, 2024
INVENTOR(S) : Christopher McFall, Alexander Cortelyou Simonson and Roger Evoy

Page 1 of 1

It is certified that error appears in the above-identified patent and that said Letters Patent is hereby corrected as shown below:

On the Title Page

In the DESCRIPTION:

Lines 1-2, change:

“Fig. 1 is a front view of the payment card with a machine-readable code surface showing our new design; and,” to --Figure 1 is a first perspective view of a first surface of the payment card having the machine-readable code on the first surface with an embedded payment card chip showing our new design.--.

Lines 3-7, change:

“Fig. 2 is a rear view thereof showing our new design. The broken lines showing a portion of the payment card with the machine-readable code surface is included for the purpose of illustrating an environmental structure and form no part of the claimed design.” to --Figure 2 is a second perspective view of a second surface of the payment on an opposite side of the payment card from the first surface showing our new design. The broken lines showing the payment card, portion thereof, or other features form no part of the claimed design. However, content shown in solid lines within the broken lines are part of the claimed design.--.
